UNITED STATES PATENT OFFICE

94,058

DESIGN FOR AN AQUARIUM

Arthur P. Swanson, Maine Township, Cook
County, Ill.

Application October 5, 1934, Serial No. 53,490

Term of patent 3½ years

To all whom it may concern:

Be it known that I, Arthur P. Swanson, a citizen of the United States, and residing in Maine Township, in the county of Cook and State of Illinois, have invented a new, original, and ornamental Design for an Aquarium, of which the following is the specification, reference being had to the accompanying drawing, forming a part thereof.

On the drawing:

Fig. 1 is a top plan view of an aquarium showing my new design.

Fig. 2 is a side elevation of the aquarium.

Fig. 3 is an end view of the aquarium.

I claim:

The ornamental design for an aquarium as shown.

ARTHUR P. SWANSON.
